Application January 15, 1944, Serial No. 518,324

17 Claims. (Cl. 123—80)

1

This invention relates to internal combustion engines and especially to engines of the class having rotatable valves in the cylinder head providing substantial portions of the combustion space at the time of firing. In particular the present invention principally contemplates the cooling of such engines and the provision of means for controlling the expansion of portions of the cylinder head adjacent the rotatable valve so as to maintain more closely or accurately the desired operating clearances between the valve and related bearing surfaces in the cylinder head.

An object of the invention is to provide an improved internal combustion engine which may be liquid cooled in efficient manner and will be compact and relatively simple in construction as well as easy to assemble.

A further object of the invention is to provide a liquid cooled engine of the rotatable valve type having means for controlling the flow of liquid coolant into the cylinder head so as to obtain more efficient cooling of surfaces or portions of the head tending to become overheated.

Another object of the invention is to control the flow of liquid coolant from the cylinder jacket to the head around the rotary valve and in such manner as to eliminate or reduce hot spots in the cylinder head.

A still further object of the invention is to baffle or block the flow of liquid coolant from the cylinder jacket cooling space to the cylinder head cooling chamber or spaces except at a predetermined point or a plurality of points so that the liquid at lower temperatures will first be directed to localities where hot spots tend to appear during operation.

Another object of the invention is to provide an engine having a rotatable valve in the head thereof and a liquid cooling jacket associated with the cylinder and extending into the head and in which the jacket surrounding the cylinder is separable at a point below the piston pin when the piston is at its extreme outer position in the cylinder, the improved construction being such that the cylinder head, cylinder and a portion of the jacket surrounding the cylinder are removable as a unit when overhauling the engine.

A further object of the invention is to provide a cylinder head constructed for mounting and operation therein of a rotatable valve, preferably of frusto-conical shape, and in which the cylinder head is constructed in improved manner to provide efficient cooling of the valve and its asso-

2

ciated parts as well as the exhaust conduit by means of a liquid coolant.

Other objects of this invention will appear in the following description and appended claims, reference being had to the accompanying drawings forming a part of this specification wherein like reference characters designate corresponding parts in the several views.

Fig. 1 is a fragmentary sectional elevation illustrating a portion of a multi-cylinder engine embodying the present invention.

Fig. 2 is a section taken substantially through lines 2—2 of Fig. 1 looking in the direction of the arrows.

Fig. 3 is a fragmentary section similar to Fig. 2 but illustrating another embodiment.

Fig. 4 is a view similar to Fig. 3 illustrating a further embodiment.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

The present invention is especially applicable to engines of the class having rotatable valves, preferably but not necessarily rotating continuously in one direction, for controlling the intake and firing of the fuel charge and for exhausting the products of combustion. In the illustrated embodiment of the invention, exemplifying one desirable adaptation thereof, a rotatable valve of the frusto-conical type is mounted in the cylinder head and is formed with substantially all or at least the major portion of the combustion chamber. The valve or rotor is formed with an opening or port in the side of the valve adapted to register with intake and exhaust passages and an ignition device during operation, there being an opening or port at the inner end or bottom of the rotor communicating at all times with the cylinder. The present invention deals especially with the cooling of the engine and provides an improved construction for circulating a liquid coolant around the cylinder and through the cylinder head whereby the temperatures of the cylinder, cylinder head and valve are efficiently controlled and adequate dissipation of heat is obtained especially at localities tending to become overheated.

In the drawings I have illustrated, by way of

example, several embodiments of the invention as applied to an internal combustion engine of the spark ignition type. However, it will be understood that the invention is not limited to an engine in which combustion is initiated by spark ignition. For most uses the engine is of the multi-cylinder type but for the purposes of simplification a single cylinder unit of the engine is illustrated in the present embodiment, it being understood that the remaining cylinders and associated parts are identical to the structure herein shown and described.

Referring to the drawings, the present engine comprises a cylinder 20 within which a suitable piston 21 is mounted for reciprocation. The piston is connected in the usual manner through a wrist pin 22 and connecting rod 23 to the crankshaft (not shown) of the engine. Surrounding a portion of the cylinder 20 is a cylindrical jacket 24 which is rigidly secured to the crankcase or forms substantially an integral portion of the crankcase. This jacket member 24 has an extended portion spaced from the wall of the cylinder 20 to provide a water cooling space or chamber 25 extending entirely around the cylinder. The cylindrical jacket 24 terminates within the height of the cylinder 20 at a point somewhat below or inward of the wrist pin 22 when the piston is at the extreme outer end of its stroke.

The lower or inner end of the cylinder 20 is formed with an annular rib 20a forming a pilot portion slidable into and having a smooth fit within the inner cylindrical wall of the lower section 24a of the jacket member 24, the rib 20a carrying sealing rings 20b to prevent leakage of the coolant between the juxtaposed surfaces of the portions 20a and 24a.

The engine is provided with a cylinder head 26 which is cast to provide a valve housing portion 27 provided with a generally frusto-conical cavity or recess, as hereinafter described, for receiving the rotary valve. The cylinder head is also cast to provide a cylinder head jacket or skirt 28 spaced from the valve housing 27 to provide a liquid cooling space or chamber 29 forming a continuation of the chamber 25. The lower or inner end of the wall or skirt 28 is formed with an annular ribbed portion adapted to cooperate with a corresponding ribbed portion formed at the outer end of the jacket member 24. When the cylinder head is assembled, the lower edge thereof is drawn down tightly against the jacket member 24, there being a gasket 30 interposed between the juxtaposed surfaces of the cylinder head and jacket adapted to be compressed to provide a liquid tight joint.

The lower or inner edge of the valve housing portion 27 of the cylinder head is formed with an annular boss or thickened portion 31, and this portion is formed with an annular groove or recess 32. The outer end of the cylinder is formed with an outwardly extending annular flange 33 extending in juxtaposed relation to the portion 31 of the valve housing. Interposed between these portions is a gasket ring 34 which may be of the copper-asbestos type capable of sustaining high temperatures and pressure. Positioned against the bottom face of the cylinder flange 33 is a flat annular baffle plate or ring 35. This baffle ring lies between the wall of the cylinder 20 and an inwardly projecting rib 28a formed on the cylinder head jacket 28, the baffle substantially bridging the space between the cylinder wall and the rib 28a so as to close off, except at any

predetermined point or locality, the passageway between the coolant chamber 25 and the chamber 29 in the head. The baffle plate or ring 35 is secured in fixed position to the bottom of the cylinder flange 33 by means of bolts 36 which in turn function to clamp the cylinder head and cylinder tightly together. Thus, when the bolts 36 are tightened sufficiently, the gasket 34 will be compressed to provide a liquid and gas tight joint and at the same time the baffle plate or ring 35 will be secured in fixed position against the bottom of the cylinder flange 33.

As illustrated in Figs. 1 and 2, the baffle plate or ring 35 is cut away at 37 to provide a communicating passageway 38 between the coolant chambers 25 and 29. In the present embodiment of the invention a single passageway 38 is provided and, hence, substantially the sole communication between the coolant chambers 25 and 29, permitting the flow of coolant from one to the other, is by means of the passageway 38. However, it will be understood that a plurality of such passageways from one side to the other of the baffle plate 35 may be provided in order to suit the cooling requirements of the particular engine. Excepting at the locality of the passageway 38, or any desired plurality of passageways, it is preferred that baffle plate or ring 35 provide such restriction at all other localities as to cause most, but not necessarily all, of the coolant head jacket into the cylinder head jacket through such passageway or passageways.

In the present embodiment the passageway 38, forming the outlet for the liquid coolant from the jacketed chamber 25 into the cooling space or chamber 29 in the cylinder head, is arranged immediately below the exhaust conduit 39 in the cylinder head. The coolant is preferably introduced into the lower end of the chamber 25 and it finds its principal outlet into the cylinder head chamber 29, as the liquid flows upwardly, through the passageway 38 and into the cooling space 29a surrounding the exhaust conduit 39. From this locality the liquid coolant flows into the remaining portions of the cooling chamber 29 which extends entirely around the valve housing 27. From this construction it will be seen that the exhaust conduit 39, which tends to become overheated during operation of the engine, will be more effectively cooled since all of the liquid coolant emerging from the chamber 25 around the cylinder will first pass through the opening 38 in the baffle plate into the cooling space 29a around the exhaust conduit, thus dissipating more effectively the heat at this locality and preventing hot spots occurring.

It will be seen that the annular flange 33 of the cylinder has an annular portion fitting into the recess 32 around the lower edge of the valve housing 27 and abutting against a shoulder formed at the inner side of the recess 32. From this construction it will be seen that the outer end of the cylinder and the valve housing portion 27 of the cylinder head have interfitting portions as a result of which it is possible to utilize the cylinder as a means for positively controlling the thermal expansion of the valve housing during operation.

The valve housing portion 27 of the cylinder head is formed with a generally frusto-conical recess 40 within which is mounted a rotatable valve or rotor 41 which is also of generally frusto-conical construction having tapering outwardly converging walls corresponding generally in shape

to the inner walls of the recess 40. The valve member 41 is formed with a side port 43 communicating with the combustion chamber 42 and adapted to register successively during rotation of the valve with a spark plug (not shown), an exhaust passage or conduit 39 and an intake conduit or passage (not shown) in the cylinder head. The direction of rotation of the valve is indicated by the arrow in Fig. 2 and the relative locations of the spark plug, exhaust passage and intake passage are shown by the radial lines 44, 45 and 46 in Fig. 2 which extend through the centers of the spark plug, exhaust and intake passages, respectively.

In addition to the side port 43 the valve 41 has a central port or opening 47 at its inner end communicating with the cylinder. The valve member 41 is also formed with a cooling chamber 48 extending entirely around the combustion chamber of the valve member. This cooling chamber is adapted to receive any suitable cooling medium such, for example, as metallic sodium, which is sealed into the chamber by means of an expanding plug 48a.

In the present embodiment the valve or rotor 41 is driven at one-half engine or crankshaft speed. It is provided with a projecting stem 49 through the medium of which the driving mechanism for the valve is connected. The valve housing portion 27 of the cylinder head is provided with an annular recess 50 in its outer end through which the valve stem 49 extends. Within this recess is located a cup-shaped spring retainer member 51 adapted to receive a compression spring 52 surrounding the valve stem 49. The outer end of the spring engages a steel coupling disk 53. This disk is formed centrally thereof with an annular set of teeth 54 meshing with corresponding teeth formed on the end of the valve stem 49. The valve stem is tapped to receive a threaded stud or bolt 55 which carries a nut 56 engageable with the coupling disk 53 and adapted to be tightened to draw down the disk and maintain its teeth 54 in constant mesh with the teeth on the outer end of the valve stem. The spring 52 is, therefore, held under constant compression so as to yieldingly hold the valve upwardly within the frusto-conical recess 40 in the valve housing. The strength of this spring and the amount of preloading thereof is such that the effort exerted by the spring to raise the valve within the valve housing is sufficient to substantially offset or equal the effort exerted during the suction stroke of the piston to draw the valve downwardly and away from its seat.

The coupling disk 53 is provided with external teeth 55 meshing with internal teeth 57a on a ring gear 57. This gear in turn has external teeth 57b meshing with the teeth of a valve driving gear 58 secured to a longitudinally extending top shaft 61. The cylinder head is formed with a housing 59 provided with a removable closure 60 for housing the driving mechanism located in the cylinder head. The top shaft 61 may be driven from the crankshaft of the engine in the manner shown and described in my application Serial No. 515,479, filed December 24, 1943.

The valve member is also preferably provided with an exterior relief area 70 extending entirely around the valve and substantially the height of the side port 43. This annular relief area may be formed either in the valve or in the wall 40 of the valve housing and may be constructed and serve the purposes in accordance with copending application Serial No. 495,260, filed July 19, 1943.

The cylinder head is formed with a series of lugs or ribs 28b bored to receive bolts 62 extending from bosses (not shown) on the jacket member 24 which, as stated, is fixed to the crankcase. The cylinder head may be drawn down tightly to the crankcase or jacket member 24 by nuts (not shown) on the bolts 62, thus connecting the jackets 24 and 28 tightly together at the water tight joint formed by the gasket 38.

It will be noted that the joint between the walls of the jacket portions 24 and 28, which joint is defined by the sealing gasket 38, lies below the wrist pin 22. By virtue of this construction and the manner in which the cylinder and cylinder head are connected together, it is possible in overhauling the engine to remove the piston without disconnecting it from the crankshaft. The improved construction permits the cylinder and cylinder head to be removed as a unit without disturbing the piston, after which the pin 22 may be withdrawn to permit removal of the piston. This is accomplished by first removing the nuts on the upper ends of the bolts 62, after which the cylinder head and cylinder may be withdrawn bodily from the cylindrical jacket 24, thereby exposing the piston sufficiently above the outer end of the jacket member 24 to permit withdrawal of the pin 22.

The embodiment illustrated in Fig. 3 is substantially the same as that shown in Figs. 1 and 2 with the exception that the passageway for the liquid coolant from the jacketed member 28 to the chamber 29 in the cylinder head is formed in the rib or flange portion 28a of the cylinder head. In this embodiment the metallic baffle plate or ring 65 corresponds substantially to the baffle plate 35 in the previous embodiment excepting that it is not cut away at 37 to provide a passageway or port opening in the plate itself. This baffle plate 65 bridges the space between the cylinder wall and the inwardly projecting edge of the rib or flange 28a cast as an integral portion of the cylinder head. The flange portion 28a of the cylinder head, which cooperates with the plate or ring 65 to baffle or block off the flow of liquid coolant from the cylinder jacket to the cylinder head jacket, is formed with a cut-out 66 which in the present instance is located beneath the exhaust conduit 39. This cut-out 66 in the casting provides a passageway 67 from the coolant chamber 25 into the portion 28a of the coolant chamber 29 whereby the liquid coolant will have its circulatory path modified so as to direct most of the cooling fluid first to the cooling space 28a around the exhaust conduit. Thence the coolant will flow into the remaining portions of the cooling space 29 around the valve housing 27.

In addition to the control of the path of flow of the liquid coolant so as to provide more uniform dissipation of heat and the elimination of hot spots in the cylinder head, another important feature of the invention resides in the manner in which very accurate control of the expansion of the valve housing 27 is achieved. In preferred practice the cylinder head (including the valve housing) is formed of an aluminum alloy whereas the rotary valve 41 and the cylinder 28 are formed of suitable ferrous metal or alloys. With this construction the valve housing will have a greater rate of expansion or a higher coefficient of thermal expansion than either the valve or cylinder, the latter two having approximately the same rate of expansion. Ordinarily the head will tend to expand more rapidly or to a greater

degree than the valve, and this occurs to a more marked degree at the lower or inner ends of the valve and valve housing, which portions are subjected to higher temperatures during operation. Any increase in the clearances between the valve and valve housing at these localities will have the undesirable result of causing oil leakage especially during the suction stroke of the piston. However, this undesirable result is largely prevented in accordance with the present invention by virtue of the flange 33 of the cylinder which has a rib portion seated in the recess 32 of the valve housing and abutting against an annular shoulder formed at one side of this recess. The flange 33 acts as a restraining abutment preventing outward movement of the valve housing relative to the cylinder. Hence, a constant control over the expansion of the housing with relation to the cylinder and valve is maintained and the desired operating clearances between the lower ends of the valve and valve housing are held substantially uniform during operation, thereby reducing materially the oil consumption.

Although in the embodiment of Fig. 3 a single passageway 66 is provided in the cylinder head flange 28a effecting communication between the jacketed chambers, it will be understood that any desired plurality of such passageways of the proper sizes and at the proper locations may be provided and are contemplated by the present invention, in order to control the flow of coolant from one chamber to the other and thereby control the temperatures of all portions of the cylinder head subject to excessive heating.

It will also be understood that the passageway or passageways providing communication between the coolant chambers in the cylinder head and around the cylinder may be provided in part in the cylinder head and in part in the baffle member 35 or 65. In other words, the baffle plate or ring and the cylinder head baffle flange 28a may both be notched or cut away at any desired point or points to form the communicating passageway or port or a plurality thereof between the chambers and to restrict the flow of coolant at other localities. Thus, in the embodiment illustrated in Fig. 4 a number of passageways 68, such as three, are provided for the flow of coolant from the cylinder jacket to the cylinder head jacket. Each such passageway is formed by a pair of arcuate notches 69 and 70 in the baffle plate or ring 65 and the baffle flange 28a respectively. As in the previous embodiments the baffle portions 65 and 28a cooperate together to restrict the flow of coolant to such an extent as to cause most of the coolant to pass upwardly through the passageways 68 into the cylinder head jacket in the region of the exhaust passage.

I claim:

1. An internal combustion engine comprising a cylinder, a cylinder jacket forming a cooling chamber around the cylinder, a cylinder head having a jacket forming a cooling chamber in the head, and baffle means providing communication for the flow of coolant between said chambers and also providing means for preventing the flow of coolant between said chambers at a predetermined locality, said baffle means including an annular plate secured to the cylinder.

2. An internal combustion engine comprising a cylinder, a cylinder jacket providing a cooling chamber around the cylinder, a cylinder head, a cylinder head jacket providing a cooling chamber in the head, and a member secured to the cylinder

substantially closing off communication between said chambers at predetermined localities and having passage means controlling the flow of coolant from one chamber to the other.

3. An internal combustion engine comprising a cylinder, a cylinder jacket providing a cooling chamber around the cylinder, a cylinder head, a cylinder head jacket providing a cooling chamber in the head, and a member interposed between the cylinder head jacket and the cylinder and secured to the latter and substantially closing off communication between said chambers at predetermined localities and having passage means controlling the flow of coolant from one chamber to the other.

4. In an internal combustion engine, a cylinder, a cylinder head having an exhaust passage, a jacketed cooling chamber in the head, a jacketed cooling chamber extending around the cylinder, and means for restricting the flow of coolant from one chamber to the other except at the locality of said exhaust passage.

5. In an internal combustion engine, a cylinder, a cylinder head, a jacketed cooling chamber in the head, a jacketed cooling chamber extending around the cylinder, and means for restricting the flow of coolant from one chamber to the other except at a predetermined locality or localities, said means including a baffle plate formed with a passageway or passageways therethrough.

6. In an internal combustion engine, a cylinder, a cylinder head, a jacketed cooling chamber in the head, a jacketed cooling chamber extending around the cylinder and means for restricting the flow of coolant from one chamber to the other except at a predetermined locality or localities, said means including a baffle carried by the cylinder head formed with a passageway or passageways therethrough.

7. In an internal combustion engine, a cylinder, a cylinder head, a jacketed cooling chamber and an exhaust conduit in the head, a jacketed cooling chamber extending around the cylinder, and means for restricting the flow of most of the coolant entering the cylinder head cooling chamber from the cylinder cooling chamber to the locality of said exhaust conduit.

8. In an internal combustion engine, a cylinder, a cylinder head, a jacketed cooling chamber and an exhaust conduit in the head, a jacketed cooling chamber extending around the cylinder, and baffle means for diverting the flow of most of the coolant from the cylinder cooling chamber into the cylinder head cooling chamber to the locality of said exhaust conduit.

9. In an internal combustion engine, a cylinder, a cooling chamber extending around the cylinder, a cylinder head having a generally frusto-conical valve housing and a cooling chamber extending around the housing, a generally frusto-conical valve rotatable in said housing, an exhaust conduit in said head adapted to communicate with a port in said valve, and baffle means for directing the coolant flowing from the cylinder chamber into the cylinder head chamber to the locality of said exhaust conduit.

10. In an internal combustion engine, a cylinder, a cooling chamber extending around the cylinder, a cylinder head having a generally frusto-conical valve rotatable in said housing, an exhaust conduit in said head adapted to communicate with a port in said valve, and baffle means for directing the coolant flowing from the

cylinder chamber into the cylinder head chamber to the locality of said exhaust conduit, said baffle means having a port communicating with said chambers and located beneath the exhaust conduit.

11. An internal combustion engine comprising a cylinder, a cylinder jacket forming a cooling chamber around the cylinder, a cylinder head having exhaust and intake passages and a jacket forming a cooling chamber in the head, and baffle means providing communication for the flow of coolant between said chambers at the locality of the exhaust passage and also providing means for restricting the flow of coolant between said chambers at the locality of said intake passage.

12. An internal combustion engine comprising a cylinder, a cylinder jacket forming a cooling chamber around the cylinder, a cylinder head having exhaust and intake passages and a jacket forming a cooling chamber in the head, and baffle means providing communication for the flow of coolant between said chambers at the locality of the exhaust passage and also providing means for restricting the flow of coolant between said chambers at the locality of the intake passage, said baffle means being carried in part by the cylinder and in part by the cylinder head jacket.

13. An internal combustion engine comprising a cylinder, a cylinder jacket forming a cooling chamber around the cylinder, a cylinder head having an exhaust passage and a jacket forming a cooling chamber in the head, and a baffle structure interposed between said chambers providing means for directing the flow of most of the coolant from one chamber to the other through passage means located in the region of said exhaust passage.

14. An internal combustion engine comprising a cylinder, a cylinder jacket forming a cooling chamber around the cylinder, a cylinder head

40

having an exhaust passage and an intake passage and a jacket forming a cooling chamber in the head, and baffle means providing communication for the flow of coolant between said chambers in the region of said exhaust passage and also providing means for restricting the flow of coolant between said chambers in the region of said intake passage, said baffle means including cooperating portions carried by the cylinder and cylinder head.

15. An internal combustion engine comprising a cylinder, a cylinder jacket forming a liquid coolant chamber around the cylinder, a cylinder head having exhaust and intake passages and a liquid coolant chamber, and means interposed between said chambers providing a passageway for the flow of coolant from one chamber to the other in the region of one of said passages, said means being constructed to substantially close off communication between said chambers in the region of the other passage.

16. An internal combustion engine comprising a cylinder, a cylinder jacket forming a liquid coolant chamber around the cylinder, a cylinder head having a liquid coolant chamber, and means interposed between said chambers for directing the flow of most of the coolant from one chamber to the other through passage means located in a region at one side of the cylinder and head.

17. An internal combustion engine comprising a cylinder, a cylinder jacket forming a liquid coolant chamber around the cylinder, a cylinder head having a liquid coolant chamber, and a baffle structure interposed between said chambers and constructed to divert the coolant so that most of the coolant will flow from one chamber to the other in a directional path through passage means located at one side of the cylinder head.

CLARENCE E. FRANK.
